UNITED STATES PATENT OFFICE.

LYDIA MARTELL AND EDWARD J. PAYNE, OF SEATTLE, WASHINGTON.

BUST-SUPPORTER.

1,020,213.

Specification of Letters Patent. Patented Mar. 12, 1912.

Application filed July 1, 1911. Serial No. 636,528.

To all whom it may concern:

Be it known that we, LYDIA MARTELL and EDWARD J. PAYNE, citizens of the United States, residing at Seattle, in the county of 5 King and State of Washington, have invented certain new and useful Improvements in Bust-Supporters; and we do hereby declare the following to be a full, clear, and exact description of the invention, such as 10 will enable others skilled in the art to which it appertains to make and use the same, reference being had to the accompanying drawings, and to the letters and figures of reference marked thereon, which form a part 15 of this specification.

This invention is a new and useful improvement in devices for holding up and supporting the bust and is designed for the use of women having heavy busts as well 20 as for the use of women having little or no bust.

The device for which a patent is herein sought is built into and made a part of the corset and is especially designed to hold up 25 and support the bust, comfortably and properly, in a correct and natural position, the corset being cut so low as to come considerably below the bust, so that the front steels cannot press upon the thorax in any manner 30 or degree, the corset, with this improvement being adapted to be worn by women having but little or no bust, in lieu of any other pads or artificial bust.

The invention is illustrated in the accompanying drawings which, with the letters of reference marked thereon, form a part 35 of this application, and in which,

Figure 1 is a perspective view of the invention, Fig. 2 is a detail view showing the 40 skeleton frame of one of the bust supporters, and Fig. 3 is a vertical sectional view.

Reference now being made to the details of the drawings by letter, A designates the stays, made of corset steel, which are disposed at inclinations and which are to extend the entire length of the corset girdle I to which the device is firmly and permanently affixed, and above said corset to such 45 points as will bring said stays A to positions immediately below the bust in natural 50

position, secured to the upper end of each stay is a wire B fastened thereto by means of clamp B', which is curved and bent to the natural shape of the bust, the ends of the wire not meeting, but ending a little distance from each other at the top of the supporter C, a fabric E covers the stays A and other fabric E' formed into a cup-like shape to fit over the bust, fills the oval formed by the wire "B" and said fabric "E'" also joins the two ends of the wire "B," permitting said oval to be expanded to the full size allowed by the wire, or to be adjusted to a smaller size by bending said wire so that the ends are close together, the fabric "E'" being folded over at the top side of the supporter when the ends of the wire "B," are close together, and making the smaller sized supporter; a strap "H" attached to the top of each supporter, and may extend over the shoulder of the wearer and be fastened to the back of the corset. This strap part of the device is for the additional support of unusually heavy busts.

What we claim to be new is:—

1. A bust supporter, comprising a corset girdle, bust supporting stays secured to said girdle, and projecting above the latter, a wire fixed to each bust supporting stay, the upper ends of said wires being spaced apart 80 and a fabric covering the wires and bringing the space between the free ends of the latter, as set forth.

2. A bust supporter, comprising a corset girdle, bust supporting stays secured to said 85 girdle, a clamping member secured to each stay, a wire fastened to each clamping member, the free ends of said wires being spaced apart, a fabric covering the stays and bridging the space between the free ends of said 90 wires, as set forth.

In testimony whereof we hereunto affix our signatures in the presence of two witnesses.

LYDIA MARTELL.
EDWARD J. PAYNE.
